(57) **CLAIM**

The ornamental design for the tape and strap cutting glove, as shown and described.

DESCRIPTION

FIG. 1 is a palm-up view of the tape and strap cutting glove of my design with a thumb portion folded onto a palm portion of said glove.

FIG. 2 is a back hand view of the tape and strap cutting glove of my design as shown in FIG. 1.

FIG. 3 is a palm edge, side view of the tape and strap cutting glove of my design as shown in FIG. 1; and,

FIG. 4 is a back hand view of the tape and strap cutting glove of my design with a thumb portion folded outward from said palm portion of said glove, wherein a cutter piece on said thumb portion is oriented above a taped box shown in broken lines.

The broken line showing of a box is for illustrative purposes only and forms no part of the claimed design.
